UNITED STATES PATENT OFFICE.

BRADFORD WEBSTER, OF LOUISVILLE, KENTUCKY, ASSIGNOR, BY MESNE ASSIGNMENTS, TO PARAGON BINDER CORPORATION, OF NEW YORK, N. Y., A CORPORATION OF NEW YORK.

BOOK.

1,274,117.

Specification of Letters Patent.

Patented July 30, 1918.

Application filed March 22, 1909, Serial No. 485,008. Renewed December 13, 1916. Serial No. 136,823.

To all whom it may concern:

Be it known that I, BRADFORD WEBSTER, a citizen of the United States, residing at Louisville, county of Jefferson, and State 5 of Kentucky, have invented a new and useful Book, of which the following is a specification.

My invention relates to books in which leaves are loosely adjusted and bound on 10 leaf-penetrating members; and the objects of my invention are to provide a simpler and more effective structure in the binder; and to provide loosely attachable means for internal compression binding.

I attain these objects by the mechanism illustrated in the accompanying drawing, in which Figure 1 is an elevation of the binder as seen from the back of the book when laid flat, the right half of the figure showing a 15 vertical longitudinal section through the center; Fig. 2, a plan of the lower base on the line 2—2 of Fig. 1; Fig. 3, a horizontal cross-section of the guide-post lock on the line 3—3 of Fig. 1; Fig. 4, an end elevation, 20 partly in section, of the binder on the line 4—4 of Fig. 1; Fig. 5, an enlarged sectional view of the first form of guide-post; Fig. 6, an enlarged section of the end of a guide-post of the second form; Fig. 7, an enlarged 25 plan in part section of the locking mechanism, using the guide-post shown in Fig. 6; and Fig. 8, a perspective of a dummy pad. Similar letters refer to similar parts throughout the several views.

The binder consists of two binding parts or bases, in each of which is set one or more leaf-retaining members and each of which is provided with openings for admitting freely the leaf-retaining members of the 30 other part to any extent, so that the bases may be pushed against each other. The leaf-retaining members of one part have means near their free ends and as far along their length as is desired for admitting an 35 engaging element of the other part. This engaging element of the other part is combined with the base and the leaf-retaining members which are set therein.

A represents the base of the binding part 40 which contains the locking slide C. The slide C is held in this casing by a cap-bar B. In the cap-bar B are set the leaf-retaining members F and F', which penetrate the inside face of the casing A and are set tightly 45 therein so as to support the cap-bar B and

the casing A in their relative positions. The locking slide C may be shorter than the casing A so as not to reach the leaf-retaining member F. The leaf-retaining member F also penetrates a slot X in the locking 60 slide C and holds it slidably against removal from the casing A.

The slide C has openings Z, the edges of which converge to allow the free passage of the lockable leaf-retaining members E and 65 E' of the other binding part when the slide is pulled out; and these same edges are adapted to engage the leaf-retaining members E and E' when the slide is pushed in.

The cap-bar B and the casing A have 70 holes suitably placed to admit freely the leaf-retaining members E and E'.

In the first form of my invention, the lockable leaf-retaining members E and E' have annular teeth near their free ends 75 which are beveled downward, and the engaging edges of the locking slide C are beveled upward, so that the locking slide will not only lock the leaf-retaining members, but the leaf-retaining members will lock the slide 80 not only by friction, but also by centerward pressure of a beveled surface on each leaf-retaining member pressing against a corresponding beveled surface in the locking slide. This tends to hold the locking slide 85 in position when the leaf-retaining members E and E' are pulled down by the expansive spring of the leaves and binder. This form is illustrated in Fig. 5.

Another form of leaf-retaining member 90 and locking slide is illustrated in Figs. 6 and 7. The inside engaging edges of the locking slide C are so shaped that the leaf-retaining members E and E' will pass freely through the slide when the slide C is pulled out. 95

When the slide C is pushed in, a narrow portion of each opening through which the members E and E' have entered, will enter the leaf-retaining members at points of small diameter, and the circular end portions of the slots will engirdle the leaf-retaining members more than half way around at points where said leaf-retaining members are of slightly larger diameter. When the locking slide C has been pushed in 105 so that the engaging edge surrounds the post E at one of its smallest points, the expansive spring of the leaves, the spring in the binder, or the elastic dummy pads, pushes the locking slide C upon the post so 110

that the engaging edge engages the post at a slightly higher point than where it entered it and at a point where the diameter of the post is slightly larger, so that the engaging edge engages the post at this point about three-fourths of the way around it, locking not only the post but also the locking slide itself until the book is compressed and the locking slide forced back downward to a point on the post where the post is of smaller diameter.

In the middle of the lower base I is fixed a spring M, adjusted to press a flat bar N toward the upper base of the binder, thus holding the leaves under contractive spring pressure. The bar N has four holes so that it will move freely up and down the four posts E, F, E', and F', and be held in alignment by them.

The covers K and K' should have their outer surfaces even with the upper and lower surfaces respectively of the bases I and A, so that there will be no improper projection when the book is placed upon the shelves in a library. The back of the book is in two thin stiff sections, crossing each other slightly when the book is open to its full expanded thickness and capable of sliding by each other.

To provide loosely attachable, cumulative means for internal compression binding and spring binding, I employ the dummy pad P, shown in Fig. 8. This pad has holes to admit the leaf-retaining members of the binder. To give it an elastic binding edge, its binding edge may consist of a strip of aerated spongy rubber R, or other spring-yielding substance. The expanded thickness of the strip R may be greater than the thickness of the remainder of the pad P, so that when it is compressed the outer part of the book will not be thicker than the book at the binding edge. If it is desirable, by reason of the spring M or the thickness of the bases A or I, to fill up some space so as to make the covers even with the back of the book, the pad P can be made thicker than the elastic strip R.

I do not limit myself to the exact form in which my invention is herein disclosed.

I claim:

1. In a filing device, a lockable leaf-retaining member, locking means therefor, a supporting member upon which said locking means is slidably mounted, and leaf-retaining means for holding said locking means slidably associated with said supporting member.

2. In a filing device, a lockable leaf-retaining member, locking means therefor, supporting members on opposite sides of the locking means, and leaf retaining means for connecting and positioning said supporting members.

3. In a loose-leaf binder or filing device,

in combination, a casing, a locking slide therein, and a leaf-retaining member; said leaf-retaining member being set in said casing and penetrating said slide; said slide having means around said penetrating member for permitting limited sliding thereof and having means for engaging a lockable leaf-retaining member; and said casing having means for admitting such lockable leaf-retaining member.

4. In a loose-leaf binder or filing device, in combination, a casing, a cap-bar therefor, a locking slide therein, and a member penetrating said casing, cap-bar, and slide, and being secured in and supporting the two first-mentioned members, said slide having means around said penetrating member for permitting limited sliding thereof; and having means for admitting and engaging a lockable leaf-retaining member; and said casing having means for admitting such lockable leaf-retaining member.

5. In a loose-leaf binder, a post-lock having a casing, a cap-bar, and a locking slide; said casing having openings adjusted in its base for the free passage of guide posts; said cap-bar having openings for the free passage of said guide posts and being adapted to hold firmly certain other guide posts; said locking slide having openings for the free passage of said latter guide posts when the slide is pushed in or pulled out, and having certain inside edges adjusted to the free passage of the first-mentioned guide posts when the slide is in one position and to engage said posts upon straight longitudinal motion of said slide.

6. In combination, a post of varying diameter near one end, and a slide having inside means for admitting said post and, upon motion transverse the post, followed by motion lengthwise the post, for creating an engagement between the post and slide whereby the slide is held by the post against all transverse motion and the post is held by the slide against longitudinal motion in one direction.

7. In combination, a post adapted near one end for admitting at a point of small cross-section and for engaging at a point of larger cross-section a locking element; a locking element having inside means for admitting said post and for creating an engagement between the post and the locking element whereby the locking element is held by the post against all transverse motion and the post is held by the locking element against longitudinal motion in one direction.

8. In combination; a post adapted near one end for admitting at a point of small cross-section and for engaging at a point of larger cross-section a locking element; a locking element having inside means for admitting said post and for creating an en-

- gagement between the post and the locking element whereby the locking element is held by the post against all transverse motion and the post is held by the locking element against longitudinal motion in one direction; and means for pushing said locking element toward the engaging portion of said post and there holding it under pressure.
9. In combination; a post adapted near one end for admitting at a point of small cross-section and for engaging at a point of larger cross-section a locking element; a locking element having inside means for admitting said post and for creating an engagement between the post and the locking element whereby the locking element is held by the post against all transverse motion and the post is held by the locking element against longitudinal motion in one direction; and spring-expansive means for pushing said locking element toward the engaging portion of said post and there holding it under pressure.
10. In combination; a post adapted near one end for admitting at a point of small cross-section and for engaging at a point of larger cross-section a locking element; a locking element having inside means for admitting said post and for creating an engagement between the post and the locking element whereby the locking element is held by the post against all transverse motion and the post is held by the locking element against longitudinal motion in one direction; and means for causing the engaging portion of the post to bear against the engaging portion of the locking element and there holding it under pressure.
11. In a pressure-bound filing device,
- loosely attachable, cumulative, resilient means for internal compression binding, and means for holding said loosely attachable elements in alignment under pressure.
12. In a binder, an elastic dummy pad, adjustable on the binder, having a strip of elastic material in its binding edge.
13. In a binder, an elastic dummy pad, adjustable on the binder, having a strip of elastic material in its binding edge, and being composed of non-elastic material throughout the balance of its structure.
14. In a binder, an elastic dummy pad, adjustable on the binder, having an elastic strip in its binding edge and non-elastic material throughout the balance thereof, said elastic strip being of different thickness from the balance of the pad.
15. In a filing device, in combination, a pair of bases, each having one or more leaf-retaining members and means for admitting freely the leaf-retaining means of the other base to any extent; and post-engaging means for holding said bases at variable distances from one another against elements filed.
16. In a filing device, in combination, a pair of bases, each having one or more leaf-retaining members and means for admitting freely the leaf-retaining means of the other base to any extent; and post-engaging means for holding said bases against elements filed at a series of different distances from one another.

Signed at Louisville, in the county of Jefferson and State of Kentucky.
